(57) **CLAIM**

The ornamental design for a bassinet tub, as shown and described.

DESCRIPTION

FIG. 1 is a perspective view of the bassinet tub embodying my new design;

FIG. 2 is a left side view thereof, the right side view being a mirror image thereof;

FIG. 3 is a top plan view thereof;

FIG. 4 is a bottom plan view thereof;

FIG. 5 is a front view thereof, and,

FIG. 6 is a rear view thereof.

FIGS. 1-6 show portions of the bassinet tub in broken lines. The broken lines are shown for environmental purposes and form no part of the claimed design.
